UNITED STATES PATENT OFFICE.

HENRY F. NELSON, OF ANGOLA, LOUISIANA.

RAIL-JOINT.

1,143,851.

Specification of Letters Patent. Patented June 22, 1915.

Application filed October 9, 1914. Serial No. 865,900.

To all whom it may concern:

Be it known that I, HENRY F. NELSON, a citizen of the United States, residing at Angola, in the parish of West Feliciana and 5 State of Louisiana, have invented a new and useful Rail-Joint, of which the following is a specification.

This invention relates to improvements in rail joints and aims to provide a joint in 10 which the fish plates are locked in a novel manner upon the rail ends.

The invention further aims to provide a joint which does not tighten as a train passes thereover and conversely, does not 15 loosen after the weight of the train has been removed therefrom. The joint is so composed that the clamping members or fish-plates may be brought into rigid contact with the rail ends, regardless of any irregularities which may occur therein and engage 20 the rail with various degrees of tightness.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made 25 within the scope of what is claimed, without departing from the spirit of the invention.

In the drawings accompanying this specification and forming a part thereof, the preferred embodiment of my invention has been 30 illustrated.

In said drawings: Figure 1 is a side elevation of the meeting ends of a pair of rails with my improved joint holding the same in rigid relation. Fig. 2 is a bottom 40 plan view of the foregoing. Fig. 3 is a cross sectional view taken on the line 3—3 of Fig. 1. Fig. 4 is a side elevation of a rail, the view illustrating the enlarged openings extending through the web of the 45 rail. Fig. 5 is a view in perspective of one of the clamping members. Fig. 6 is a view in perspective of the other coöperating clamping member. Fig. 7 is a view in perspective of the locking key by means of 50 which the locking ring is held against accidental rotation.

Referring to the drawings in which similar reference numerals designate corresponding parts throughout the several 55 views, the meeting ends 8 of a pair of rails,

are shown as provided with spaced apertures 9 extending through the webs thereof.

The joint comprises two clamping members or fish plates 10 and 11, each of which is provided with a number of upstanding trapezoidal projections 12 equipped in the respective fish plates with coöperating pins and sockets 13 and 14. These pins 13 are adapted to project through the apertures 9 in the webs of the rails and fit loosely therein so as to allow for the expansion and contraction of the rails due to thermal causes. The clamping members or fish plates 10 and 11 are of that type in which an under or bottom plate 15 projects beneath the rail 60 flange. These under or bottom plates are provided respectively with semi-circular plates or bosses 16 and 16', the curved edges of which are beveled as at 17.

A locking ring 18 is shown and the same 75 is provided with an undercut central opening 19 comprising two semi-circular and offset portions 20 and 21. Thus two diametrically opposed shoulders 21' are defined in the ring 18. The relative position of the 80 plates 16 and 16' is such that when the clamping plates 10 and 11 engage the rail ends and when the pins 13 extend through the rail apertures 9 and the openings 14, the parts 16 and 16' will be offset, as illustrated in Fig. 2. The locking ring 18 may be readily positioned upon the plates 16 and 16' with the shoulders 21' close to the offset edges of the plates. Then a rotation of the 85 ring will draw the clamping members 10 and 11 together, transversely, and thus securely lock the ends of the rails in rigid relation.

In order to effect a forced rotation of the locking ring it is provided with wrench engageable portions 22 in the form of outstanding teeth which may be engaged by a spanner. One of the fish plates is provided with a slot 23 adapted to register with any one of a series of slots 24 which are provided in the locking ring 18. A key 25 is driven down 95 through the fish plate aperture 23 and enters one of the apertures 24 with which the ring 18 is provided. The key 25 is thus adapted to lock the ring against rotation. The undercut and beveled walls of the locking ring 18 and the plates 16 and 16' prevent the locking ring from being accidentally detached. The portions 20 and 21 which form the central opening 19 of the ring 18 are of relatively greater diameter than the diameter of 100 105 110

the plates 16 and 16', thus allowing the ring to be readily removed or replaced when the ring is concentric with the plates 16 and 16'. The rotation of the ring 18 alters these conditions and results in the plates 10—11 being drawn into rigid relation to clamp the rail ends therebetween.

Having thus described my invention, what I claim is:—

- 10 1. In a device of the class described, a pair of fish plates provided with locking bosses; and a locking ring rotatable on the bosses, the locking ring engaging the bosses with a cam-like action.
- 15 2. In a device of the class described, a pair of fish plates provided with locking bosses; a locking ring rotatable on the bosses, the locking ring engaging the bosses with a cam-like action; and means for holding the ring 20 against rotation.
- 25 3. In a device of the class described, a pair of fish plates provided with locking bosses; a locking ring rotatable on the bosses, the locking ring engaging the bosses with a cam-like action; and a key engaging one fish plate 30 and the ring to hold the latter against rotation.
- 35 4. A device of the class described, comprising clamp members adapted to receive the rail ends and engage the same, locking plates carried by said clamp members, and a locking ring engaging said locking plates drawing the same, and the clamp members, together. 40
- 45 5. A device of the class described, comprising clamp members adapted to receive the rail ends and engage the same, locking plates carried by said clamp members, a locking ring engaging said locking plates drawing the same, and the clamp members, together, 45 and means for holding said ring against rotation.
6. A rail joint comprising fish plates, locking plates projecting therebeneath and offset one with relation to the other, a locking

ring with offset communicating apertures engaging said locking plates and drawing the same together by cam-like action.

7. A rail joint comprising a fish plate with semi-circular locking plates offset one with relation to the other, and meeting along straight diametric edges, the curved edges of said plates undercut, a locking ring with a central opening formed of two communicating offset apertures with undercut walls 55 adapted to engage said locking-plates to hold the same rigidly together.

8. A rail joint comprising a fish plate with semi-circular locking plates offset one with relation to the other, and meeting along straight diametric edges, the curved edges of said plates undercut, a locking ring with a central opening formed of two communicating offset apertures with undercut walls 60 adapted to engage said locking-plates to hold the same rigidly together, and a key engaging said locking ring and a fish plate, holding said locking ring against accidental rotation.

9. A rail joint comprising a fish plate with semi-circular locking plates offset one with relation to the other, and meeting along straight diametric edges, the curved edges of said plates undercut, a locking ring with a central opening formed of two communicating 75 offset apertures with undercut walls adapted to engage said locking-plates to hold the same rigidly together, a key engaging said locking ring and fish plate, holding said locking ring against accidental rotation, said 80 ring provided with a wrench engageable portion for its forced rotation.

In testimony that I claim the foregoing as my own, I have hereto affixed my signature in the presence of two witnesses.

HENRY F. NELSON.
